(57) **CLAIM**

The ornamental design for a connector for a surgical instrument, as shown and described.

DESCRIPTION

FIG. 1 is a perspective view of a connector for a surgical instrument in accordance with the new design;

FIG. 2 is a rear perspective view of the connector of FIG. 1; FIG. 3 is an exploded perspective view of a portion of the connector for a surgical instrument of FIG. 1;

FIG. 4 is an enlarged perspective view of a male portion of the connector for a surgical instrument of FIG. 1;

FIG. 5 is a front view of the male portion of the connector for a surgical instrument of FIG. 4;

FIG. 6 is a rear view of the male portion of the connector for a surgical instrument of FIG. 4;

FIG. 7 is a left side view of the male portion of the connector for a surgical instrument of FIG. 4;

FIG. 8 is a right side view of the male portion of the connector for a surgical instrument of FIG. 4;

FIG. 9 is a top plan view of the male portion of the connector for a surgical instrument of FIG. 4;

FIG. 10 is an enlarged perspective view of a female portion of the connector for a surgical instrument of FIG. 1;

FIG. 11 is a front view of the female portion of the connector for a surgical instrument of FIG. 10;

FIG. 12 is a rear view of the female portion of the connector for a surgical instrument of FIG. 10; and,

FIG. 13 is a bottom plan view of the female portion of the connector for a surgical instrument of FIG. 10.

The even length broken lines in the figures are directed to portions of the connector for a surgical instrument that form no part of the claimed design. The dot-dashed lines show unclaimed boundaries and form no part of the claimed design. The dot-dashed lines in FIG. 3 between the two connector pieces show the order of assembly.
